UNITED STATES PATENT OFFICE.

JAMES MELVIN JONES, OF BUFFALO, NEW YORK.

SAFETY-GUARD FOR STAMPING-MACHINES.

976,181.

Specification of Letters Patent. Patented Nov. 22, 1910.

Application filed October 25, 1909. Serial No. 524,342.

To all whom it may concern:

Be it known that I, JAMES MELVIN JONES, a citizen of the Dominion of Canada, temporarily residing at 1443 Niagara street, in the city of Buffalo, in the State of New York, United States, have invented a certain new and useful Safety-Guard for Stamping-Machines; and I do hereby declare that the following is a full, clear, and exact description of the construction and operation of the same.

The invention relates to a very simple but effective safety guard attachment to stamping machines that is calculated to protect the hand of an operator from injury while operating the machine.

The invention consists essentially of a guard rod caused to move back and forth horizontally between the dies, when separated, of a stamping machine, while in operation, and mechanism so arranged as to cause the safety rod to automatically move forward as the dies are coming together, and if the operator's fingers are on the lower die (as is often the case) the safety rod will push his finger off said die before the dies come together, and prevent the operator's fingers from being caught between the dies. A tube is made to encircle the said safety rod, to carry a flat brush that is attached thereto, and mechanism constructed to turn the brush from perpendicular to horizontal, and vice versa, so as to brush off the work operated on from the lower die (after stamping) when in a vertical position, and turned to a horizontal position on its return in time to brush off the next piece stamped from the lower die, when completed, as will be more fully shown hereinafter and illustrated in the accompanying drawing in which,—

Figure 1, is a side elevation of a stamping press with my safety attachment connected thereto. Fig. 2, is a similar view showing the operator's hand pushed away from the dies by the safety rod, before the upper and lower dies come together. Fig. 3, is a side elevation of the mechanism employed to operate the safety rod and brush, detached from the stamping machine. Fig. 4, is a side view, partly in section of the gear frame, carrying the attachment, but detached from the stamping machine. Fig. 5, is an end view of the same. Fig. 6, is a side

view of safety rod and brush and device 55 for oscillating the brush. Fig. 7, is a front view of the mechanism to move the brush. Fig. 8, is a top view of the upper end of Fig. 3. Fig. 9, is a cross section of a picker used sometimes instead of a brush. Fig. 60 10, is a rear view of the cap into the recess of which the slanting rack bar operates. Fig. 11, is an end view of the same. Fig. 12, is a cross section of safety rod, tube and brush.

In the drawing A, represents a portion of an ordinary stamping machine carrying a male die 2, and a female die 3. 4, Fig. 1, represents the right hand of an operator in the act of placing a blank form on the female or lower die 3, while the male die 2, is being elevated in position for a downward stroke.

5, Fig. 2, represents the safety rod which is thrown forward between the dies and has 75 automatically pushed the operator's hand off the female die 3, before the male die has reached the lower die. The mechanism to operate the safety rod back and forth may be described as follows. The safety rod 5, 80 is passed through a tube 6, and in the said tube is inserted a flat brush 7^a, the object of the brush being to push the finished work off the female or lower die 3, on its forward movement, and while the bristles of the 85 brush are in a vertical position, and means also are made to turn the brush bristles horizontally on the return of the brush to the rear of the dies to be in a position for another forward movement when the dies separate. The said safety rod 5, is connected to a double bracket 8, and held thereto by a set screw 9, at the lower end of the said bracket.

10, is a horizontal rack bar, having a cylindrical pin 11, passing through one end of it 95 and secured thereto by a set screw 12, said pin being made to pass through a circular hole 13, in the projection of the bracket 8. The inner end of the said rack bar 10, is made to pass through a metal frame 14, 100 which is rigidly attached to the side of the stamping machine by bolts 15, 15. The said frame 14, has within it a large gear wheel 16, which meshes into the cogs of the rack bar 10, and moves it with the safety rod 5, 105 back and forth horizontally between the dies 2, 3, when they are separated. 17, is a smaller gear wheel also on the same shaft

18, which carries the large gear wheel 16; it is about half the size of the gear wheel 16, and may be integral with it or be separate, but keyed on the same shaft as the said 5 gear wheel 16.

19, is an upper and slanting rack bar made to mesh in the small gear wheel 17, and drive it, with the large gear 16, to operate the lower rack bar, and thence the safety rod 5 10 and brush 7^a. The angle of the said rack bar 19, is adjustable according to requirements, it passes through a groove 20, formed in an adjustable cap or projection 21, which is pivotally attached to the axle 18, of the 15 gear wheels 16 and 17, in the frame 14. The angle of the said groove 20, in the projection 21, to adjust the proper slant of the upper rack bar 19, is accomplished by means of two curved slots 22, and 23, in the frame 14, and 20 bolts 24, 25 are passed through the cap or projection 21, and through the slots 22, and 23, and secured by nuts at the rear of the frame 14; this means permits of adjusting the said slanting toothed rack bar 19 to any 25 required angle.

26, is a thumb screw placed on the outer end of the axle 18, by which to tighten the lower part of the said cap or projection 21, to the frame 14. The upper end of the said 30 toothed rack bar 19, is pivotally secured to a wrist connection 27, held by a nut 28, the said wrist pin connection being secured to a link 29, the two latter being held together by a set screw 30. The said link 29, has a 35 connecting rod 31, made to pass through it and held at any part of its surface by a set screw 32. The opposite end of the said connecting rod 31, is passed through another link 33, (similar to the one marked 29), and 40 is held thereto at any desired distance from the said link 29, by a set screw 34. The upper end of the link 33 has a circular opening made therein and a connecting rod 35, passed through it and secured to the said link 33, by 45 a set screw 36. The opposite end of the connecting rod 35, has a metal head piece 37, secured thereto through which is made to pass a pin 38, which has a nut 39, screwed on the outer end of it, and a head 40, at the 50 opposite end. The pin 38, is made to pass through a slot 41, in a plate 42, the said slotted plate having at its rear side a groove 43, into which the head 40, of the bolt 38, lies countersunk, and admits of the bolt to 55 be adjustably changed from one spot to another to alter the throw of the safety rod 5. The said pin or bolt 38, is held to the plate 42, by its head 40, on the inside, and the nut 39, on the outside of the plate 42. The said 60 plate 42, is bolted to the end of the shaft 45, of the stamping machine, by three bolts 44, and as the said shaft revolves the plate 42, revolves with it, and as the position of the pin 38, in the slot 41, of the plate 42, is 65 placed, so will the throw back and forth of

the safety rod 5, through the connecting rods, gears and rack bars, be lengthened or shortened.

Mechanism for turning the brush from a horizontal to a vertical position alternately.—The brush 7^a, is secured in a horizontal slot 7, of the tube 6, which incloses the safety rod 5. A crank plate 46, is secured to the inner end of the tube 6, inclosing the guard rod 5, and is movably connected to the end of a rocker arm 47, having a slot 48, in its upper end through which the pin 49, of the crank plate 46, passes to make the connection between the two said parts. The rocker arm 47, is pivoted about the center, to the bracket 8, by the pivot pin 50, and its lower and smaller end is made to pass through a slot 51, formed in the outer end of a movable metal bar 52, fastened alongside of the lower rack bar 10, and the 75 said metal bar 52, moving horizontally with the said rack bar 10, operates the rocker arm 47, back and forth, and through the latter oscillates the tube 6, and causes the brush 7^a, (which is attached to the tube) to change 80 from a vertical to a horizontal position. When the said brush 7^a is in an upright position it sweeps off the work stamped, from the face of the lower die, and on its return to the front it is turned flat as it passes between the dies on the rising of the upper die 2, as shown in Fig. 2.

Brush.—The means of securing the brush 7^a, to the tube 6, is as follows, two metal strips 6^a, inclining inward at the top are 100 soldered to the tube, leaving a longitudinal channel 7, the length of the tube into which the head of the brush is inserted and may be pushed along to any part of the said tube 6 desired, to operate over the under die 3, 105 of the stamping machine A. It may be here observed that the said brush 7^a, attached to the tube 6, surrounding the safety rod 5, will remove from the dies the majority of 110 different pieces of work after being stamped, but for some special individual work, the brush would be removed and a small instrument as a picker 54, Fig. 9, inserted in its place the same formed of iron or steel, 115 placed in any way desired on the tube, and made to run under the work being stamped, to tip and push it off the under die at the rear end of the machine, and having the same action as the brush.

Tension spring.—A flat spring 55, is 120 placed in a recess in the base portion of the frame 14, in the inside, made to impinge on the said sliding rod 52, to give it sufficient tension to operate on the brush 7^a.

Having thus described my device and its 125 advantages, what I claim as my invention and desire to secure by Letters Patent, is—

1. In combination with a die stamping machine, a brush made to operate back and forth in parallel lines between the male and 130

female dies during the operation of stamping and push the operator's hand off the lower die before the upper die descends to it and remove the stamped work off the female die on its return rearward, and timed mechanism to operate the brush to produce this result.

2. In combination with a stamping machine, mechanism attached thereto and operated by it, consisting of a frame attached rigidly to the stamping machine, a horizontal rack bar made to slide back and forth in the said frame, a horizontal safety rod attached indirectly to the rack bar, a brush attached 15 to a tube surrounding the safety rod, and mechanism to drive the horizontal rack bar to push the said safety rod and brush between the dies when separated during their operation, to push the operator's hand off 20 the lower die before the upper die descends to it, and on the return movement to brush off the work stamped as the upper die ascends preparatory to another descent.

3. In combination with a stamping machine, a frame attached to the machine, carrying a large and small pinion, a horizontal rack bar made to slide back and forth in a groove in said frame, a safety rod attached indirectly to the said rack bar, to move forward and back between the dies, when apart, a slanting rack also made to slide diagonally in a groove in the said frame and made to engage with the smaller gear wheel, the said slanting rack bar indirectly connected to and 35 be driven by the main shaft of the stamping machine for the purpose specified.

4. In combination with a stamping machine, a plate secured rigidly to the end of main shaft of a stamping machine, a longitudinal slot and recess in said plate, the head piece of a connecting rod attached to the plate by a bolt made to pass through it and the slot of the plate, and means to hold the bolt to any part of the slot of said plate, a 45 series of adjustable connecting rods secured to the said slotted plate and to the slanting rack-bar, the latter made to engage with a small gear pinion in the frame, and operate the large pinion wheel, horizontal rack bar 50 and safety rod for the purpose specified.

5. In combination with a stamping machine, and safety rod to move back and forth between the dies during their operation, a series of connecting rods made to pass 55 through links to adjust the length of the connection between the slotted plate on the main shaft of the stamping machine and the gears, to alter and adjust the distance throw of the safety rod and brush between 60 the dies.

6. In combination with a stamping machine, and mechanism to operate a safety rod forward and back between the dies when they are separated, a crank on the inner end 65 of the safety rod, a device to hold a brush on

the safety rod, a rocker arm attached to the said crank a slot in same to receive the crank pin, a bracket to hold said parts, a horizontal bar attached to the side of the horizontal rack bar, and made to receive the small end 70 of the rocker arm to impart motion from the same by the said rack bar, and give a quarter turn to the safety rod to turn the brush horizontal when passing outward between the dies, and perpendicular when returning, 75 to sweep off the stamped work from the lower die as soon as the upper die ascends.

7. In combination with a stamping machine, a safety device made to operate between the male and female dies when they 80 are apart, and mechanism to give the safety device one quarter turn during every forward and backward movement to push off the operator's hand from the lower die before the dies close together and sweep off the 85 stamped work from the lower die on the return or backward movement of the brush.

8. In combination with a stamping machine, and mechanism to operate a safety rod and stamped work removing device 90 between the male and female dies when apart, of slots in the frame inclosing the bevel gear, a cap to fit over the same, said cap having a groove in which the slanting rack bar slides, the bolts of the cap to enter the 95 slots so as the cap and its groove can be adjusted to any angle or slant required by the said slanting rack bar.

9. In combination with a stamping machine, an attachment consisting of a safety 100 rod and devices attached thereto, to drive it back and forth between the dies when apart, a frame carrying gears, an adjustable cap on the upper part of said frame, a groove in said cap, a slanting adjustable rack bar 105 made to slide therein, slots in the upper part of the frame to adjust the angle of the groove for the slanting rack bar, a horizontal recess in the frame for the lower and horizontal rack bar to slide in, an interior 110 recess, a flat tension spring in the latter to impinge on the lower rack bar, a cover guide plate, secured to the lower part of the frame to keep the horizontal bar and gear wheels in place.

10. In combination with a stamping machine, and mechanism to operate a safety rod and brush picker between the male and female dies, a frame carrying gear wheels, a slanting rack bar made adjustable to parts 120 attached to the slotted plate secured to the main shaft of the stamping machine to operate the rack bar.

Signed at Hamilton, Ontario, this 21st day of May, 1909.

JAMES MELVIN JONES.
